(57) **CLAIM**

The ornamental design for a cargo box for portable robot, as shown and described.

DESCRIPTION

FIG. 1 is a perspective view of a cargo box for portable robot according to the present invention.

FIG. 2 is a perspective bottom view of a cargo box for portable robot according to the present invention.

FIG. 3 is a front view of a cargo box for portable robot of FIG. 1.

FIG. 4 is a rear view of a cargo box for portable robot of FIG. 1.

FIG. 5 is a left side view of a cargo box for portable robot of FIG. 1.

FIG. 6 is a right side view of a cargo box for portable robot of FIG. 1.

FIG. 7 is a top view of a cargo box for portable robot of FIG. 1; and,

FIG. 8 is a bottom view of a cargo box for portable robot vehicles of FIG. 1.

1 Claim, 8 Drawing Sheets
